UNITED STATES PATENT OFFICE.

LEO E. EVSLIN, OF NEW YORK, N. Y., ASSIGNOR, BY MESNE ASSIGNMENTS, TO LEE
SURGICO-DENTAL M'F'G CO., INC., A CORPORATION OF NEW YORK.

ARTIFICIAL TOOTH.

1,202,980.

Specification of Letters Patent. Patented Oct. 31, 1916.

Application filed May 20, 1915. Serial No. 29,270.

To all whom it may concern:

Be it known that I, LEO E. EVSLIN, a subject of the Emperor of Russia, residing in the United States, in the city, county, and State of New York, have invented certain new and useful Improvements in Artificial Teeth, of which the following is a specification, reference being had to the accompanying drawing.

10 My invention relates to artificial teeth, and more particularly to artificial teeth of the class known as interchangeable or replaceable teeth, and comprises certain new and useful improvements in the construction of such teeth, in the backings therefor, and in the mode of securing the backings to the teeth.

A principal object of my invention is to produce an artificial tooth of the kind indicated adapted to afford maximum strength for masticating purposes, as well as maximum strength in attachment to the roots of the natural teeth by which such artificial teeth are supported in that form of artificial denture known as crown work, and for attachment to suitable abutments in that form of artificial denture known as bridge work, without the exhibition of any gold or other metal work in connection with the teeth when the latter are in position in the mouth of the wearer, thereby conserving one of the most important advantages of artificial teeth formed of porcelain or other similar material, namely, their simulation 35 of the natural teeth with complete invisibility of all metal work whatsoever necessarily employed in connection therewith.

Further objects of my invention are to form an artificial tooth of porcelain or other similar material in such manner as to make it substantially self-retaining as regards its metallic backing in order that the cement used in uniting the tooth thereto may serve merely as a binding material 40 between the porcelain and the metal, and to form the back or lingual portion of the porcelain tooth in such manner as to minimize the chance of relative displacement between the tooth and the backing due to 45 the motion of the jaws in mastication, and to so form that portion of the tooth as to

enhance its holding capacity with relation to its backing, and to assist in its stability with regard to the natural tooth or abutment to which the latter may be affixed, in such 55 manner that entire reliance for supporting the artificial tooth in relation thereto need not be placed solely in the post or pivot, but that the tooth itself shall assist the post or pivot in maintaining the artificial 60 denture in fixed relation to the support to which it may be attached.

My invention further includes all the other various novel features of construction and arrangement hereinafter more definitely 65 specified.

In the accompanying drawing I have illustrated in Figures 1 to 7, inclusive, a preferred manner of carrying out my invention as applied to a cuspid tooth, Fig. 1 70 being an enlarged side elevation of the tooth with its backing and supporting pin in place; Fig. 2, a side elevation of a similar tooth, the backing, however, being shown in central vertical section; Fig. 3, a central, 75 vertical section of the backing removed from the tooth; Fig. 4, a central, vertical section through the tooth with the backing and pin in place; Fig. 5, a rear elevation of the tooth, with the backing and pin in position; Fig. 6, a bottom plan view of the tooth, with the backing and pin in position, and Fig. 7, a rear elevation of the tooth, with the backing and pin removed therefrom. In Figs. 8 to 14, inclusive, are shown 80 corresponding views of the invention in connection with a molar tooth, Fig. 8 being a side elevation of the tooth with the backing and pin in position; Fig. 9, a side elevation of the tooth with the backing shown in 85 central, vertical section; Fig. 10, a central, vertical section of the backing removed from the tooth; Fig. 11, a central, vertical section through the tooth, with the backing and pin in position; Fig. 12, a rear elevation of 90 the tooth, with the backing and pin in position; Fig. 13, a bottom plan view of the tooth, with the backing and pin in position, and Fig. 14, a rear elevation of the tooth, with the backing and pin removed therefrom. 95 In Fig. 15 is shown a slightly modified form of the device illustrated by a central, verti-

cal section through a cuspid tooth, and in Figs. 16, 17 and 18 is shown a substantially similar modified form as applied to a molar tooth; Fig. 16 showing the tooth in side elevation, with the backing and pin in position; Fig. 17, the tooth in side elevation, with the backing in central, vertical section, and Fig. 18 the backing in central, vertical section removed from the tooth, these figures corresponding respectively to Figs. 8, 9 and 10 illustrating the preferred form of construction as applied to a molar tooth, and Figs. 1, 2 and 3 as applied to a cuspid tooth. In Fig. 19 is a perspective view of a form of pin or pivot of the form which I prefer to employ.

For the purpose of attaining the several objects of my invention, I form the rear or lingual portion of an artificial tooth composed preferably of porcelain or other desired material in such manner that the same shall present a substantially square or rectangular outwardly projecting abutment which affords a substantial and adequate support for the metal backing upon which the tooth is mounted, and while I may construct the lingual portion of the tooth in any manner suitable and effective for accomplishing the results desired, I prefer to form the same substantially as shown in the drawing in which the invention is illustrated in connection with both cuspid and molar teeth, the method of forming the teeth hereinafter described in regard to the latter being also suitable for use in connection with bicuspid teeth as well.

Referring now more especially to Figs. 1 to 7, inclusive, in which the invention is illustrated as applied to a cuspid tooth 1, having a cutting edge 2 and a cervical border 3, the tooth proper being formed of porcelain or similar material in the well-known manner, the tooth is provided at its rear or lingual portion with a plurality of inwardly cut and suitably disposed V-shaped grooves, one of these grooves 6 extending substantially transversely across the tooth adjacent the cervical border and being inwardly and upwardly directed, while a similar groove 8 also extends transversely across the tooth somewhat below the rubber line indicated at 10. Extending upwardly from the ends of the groove 6, substantially parallel with the labial face 12 of the tooth and to a point about two-thirds of the distance from the cervical border 3 to the cutting edge 2 and on either side of the tooth, I provide an inwardly directed shoulder 15, and from the upper ends 16 of which and extending rearwardly substantially parallel with the upper lingual surface 18 to meet the ends of the groove 8, I provide another inwardly directed shoulder 20 on either side of the tooth extending from the end 16 of

the shoulder 15 to the end of the transverse groove 8. The sides 22 of the tooth between the shoulders 15 and 20 are preferably somewhat indented or depressed for a depth equal to that of the shoulders, as best shown in Fig. 7. If desired the grooves instead of being made of constant depth, may be made deeper toward their central portions and shallower toward their ends, the latter gradually merging into their adjacent surfaces instead of terminating abruptly. It will be evident that the direction and formation as well as the depth and configuration of the several grooves and shoulders will necessarily be somewhat varied in different sizes and shapes of cuspid teeth, but the substantial arrangement and direction thereof should preferably be preserved as far as possible so that a relatively rectangular outwardly and rearwardly projecting base or abutment 25 will be defined thereby to afford a firm and substantial seat for a considerable portion of the metal backing 30. This backing, which may be formed of sheet gold, platinum or other suitable material, is preferably constructed by swaging the material over the tooth 1 formed as previously described, or over a suitable replica of the same, the metal during this operation being snugly forced into all of the various grooves and depressions hereinbefore described to perfectly conform to the same, and being turned outwardly over the sides of the tooth adjacent the shoulders 15 to form suitable side lips 32 extending on either side of the tooth from adjacent the cervical border thereof to the points 16, at the upper ends of the shoulder 15, another upwardly turned posterior lip 34 being also formed to surround the upper lingual portion 18 of the tooth, as best shown in Fig. 1, and extending from either point 16 completely around the tooth to the corresponding point upon the opposite side thereof. It will be evident that a backing formed as described will completely cover and inclose the indented and grooved portions of the tooth, and will afford a substantial and adequate support to the various parts thereof, and form a suitable backing therefor and that by reason of the disposition and arrangement of the grooves and shoulders upon the tooth, the backing will tend to adhere to the tooth when in operative position thereon without the aid of cement or other artificial fastening means, and will thus assist such means, when employed in practice, in maintaining the backing and tooth in fixed relation.

The tooth may be provided with an upwardly projecting socket 40 suitable for the reception of a pin or pivot 41, having a flanged head 42, said pin being preferably formed slightly oval in shape in order

to prevent rotation relative to the tooth when positioned therein. The backing is also provided with a suitable aperture 45 for the passage of the pin, the material forming the backing adjacent the aperture being preferably disposed in such manner as to form an inwardly directed flange 46 surrounding the aperture, the tooth 1 being provided with a suitably disposed 10 opening 48 for the reception thereof when the backing is in position thereon, in which position, as best shown in Fig. 4, the flanged head 42 of the pin 41 will rest against the outside of the backing, preferably substantially at the center of the rectangular outwardly projecting portion 25 of the tooth and corresponding portion of the backing, in which position the pin may be secured by suitable cement (not shown) or in any 20 other preferred manner as understood by those skilled in the art.

In Figs. 8 to 14, inclusive, is illustrated the preferred form of my invention as applied to a molar tooth as distinguished from 25 a cuspid tooth hereinbefore described, and in view of the extended description already given of the invention as applied to a cuspid tooth, it is believed that the application of the same to a molar tooth would be entirely 30 clear to those skilled in the art without any description thereof. Briefly, however, a molar tooth 60, having a masticating surface 61, and cervical border 62, and formed of porcelain or other suitable material, is provided with upwardly extending, inwardly directed shoulders 64 on either side, from the ends of the lower transverse inwardly and upwardly directed groove 65 corresponding to groove 6 on the cuspid tooth to a point 67 35 about two-thirds of the distance from the cervical border 62, to the masticating surface 61 of the tooth. The shoulders 64 may preferably extend in a slightly convex formation in opposition to the somewhat convex 40 labial face 68 of the tooth. From either point 67 at the upper ends of the shoulders 64 and extending backwardly on either side of the tooth to meet the upper transverse groove 69 corresponding to groove 20 al- 45 50 ready described in connection with the cuspid tooth is an inwardly directed shoulder 70 substantially parallel with the upper surface of the tooth and located a short distance below the same, the sides of the tooth 55 between the shoulders being preferably indented or depressed to a depth equal to that of the shoulders, similarly to the cuspid tooth previously described to form surface 71. By forming the tooth in the manner indicated 60 there is thus presented a substantially rectangular outwardly projecting base 72 defined by the various shoulders and grooves similar to the base 25 already described and suitable for the reception of the correspond- ing portion 75 of the backing 76, which may 65 be swaged up as hereinbefore described in connection with the cuspid tooth, and which comprises the side lips 78 engaging the lateral sides of the tooth and posterior lip 80 surrounding the lingual portion of the tooth 70 below the masticating surface, which latter lip may preferably be made relatively deeper in a vertical direction than the corresponding lip 84 upon the cuspid tooth, thereby increasing the effective surface of the backing. 75 A suitable socket 82, preferably upwardly and inwardly directed, is formed in the body of the tooth for the reception of the pin 41 which passes through an opening 84 in the backing and may be secured within 80 the tooth in a manner similar to that previously described in connection with the cuspid tooth, said socket being preferably surrounded with an inwardly directed flange 85, corresponding to flange 46 in the backing 85 for the cuspid tooth. The teeth, either cuspid, molar or bicuspid, having been formed and assembled upon their respective backing as previously described, and preferably secured thereto with suitable cement, may be 90 positioned upon the support designed therefor by use of any of the various means known to persons skilled in the art, as for instance, by soldering the backing and pin head 42 to the support or abutment, or in any other 95 desired way, it being evident that when the tooth is secured in position thereon that the backing will securely and rigidly support the porcelain portion in such manner that accidental displacement of the same with relation to the backing, or support to which the backing is attached, is practically impossible. It will be further evident that if the porcelain portion of the tooth be thereafter 100 damaged in any way, and it be desired to replace the same, the porcelain tooth may be readily detached from the backing, and a new one supplied of course formed in a similar manner to the old porcelain so as to 105 properly engage the various convolutions of the backing to which it may preferably be secured by means of suitable cement in the well-known manner.

In Figs. 15, 16 and 17, corresponding to Figs. 8, 9 and 10, is illustrated a slightly 115 modified form of the invention as applied to a molar tooth, and which comprises a plurality of upper transverse grooves 90 and 91 one above the other instead of the single groove 69 previously described, and the 120 ends of each of which are respectively connected to the point 67 by the inwardly directed shoulders 94 and 95 on either side of the tooth. When this construction is employed the surfaces 98 defined between the 125 two shoulders 94 and 95 will be not quite so deeply indented or depressed as the surface 99 between the shoulder 95 and shoulder 64,

and which corresponds to surface 71, and by forming the tooth in this manner the effective supporting surface for the backing is materially increased and the rectangular portion 100 is formed. Furthermore, it will be evident that, if desired, three or more transverse grooves may be employed respectively connected to point 67 by suitable shoulders. In Fig. 18 a similar modified 10 form of the invention is illustrated as applied to a cuspid tooth, a plurality of upper grooves 96 and 97, corresponding to grooves 90 and 91, being formed in the tooth, and extending to the upper ends of the upwardly 15 directed shoulders extending from adjacent the cervical border of the tooth toward the cutting edge thereof, a construction which it is believed will be clearly comprehended from the foregoing description of the similar 20 modified form applied to a molar tooth and illustrated in Figs. 15 to 17, inclusive. It will be understood that in these modified forms of the invention the backing is formed in such manner that it will snugly engage in 25 the various grooves, shoulders and depressions formed in the tooth in a manner similar to that previously described in connection with the preferred forms of the invention, and that suitable sockets will be provided 30 in the tooth for the reception of the pivot pin 41 and surrounding flange on the backing as hereinbefore described.

It will be evident that by slightly varying the direction and depth of the grooves, 35 shoulders and depressions upon any given tooth, that the projecting, substantially rectangular portion of the tooth against which the backing abuts may be arranged to project from the tooth in varying angular relation therewith as may be desired, without departing from the spirit of the invention, and it will be further evident that various other minor changes in the shape and construction of the various parts of the device 40 and in the materials which may be utilized to form the same in order to adapt the invention to the varying conditions found in practice may be made without departing from the spirit and scope of the invention 45 and as defined in the appended claims.

Having thus described my invention, I claim and desire to protect by Letters Patent of the United States:

1. The combination of an artificial tooth 55 formed of porcelain or the like having an undercut transverse groove in the lingual face of said tooth and extending substantially parallel to the rear lingual edge of said tooth, a surface of said groove being a 60 substantially plane surface slightly inclined from the lingual portion of said tooth toward the front or outer edge of the articulative portion of said tooth to form an un-

dercut seat, and a metal backing for said tooth covering the rear side of said tooth 65 and fitting against said surface of said groove.

2. The combination of an artificial tooth formed of porcelain or the like and having a plurality of inwardly directed transverse 70 grooves and an outwardly projecting, substantially rectangular portion, and a metallic backing operative to engage said grooves and to inclose said portion and comprising a plurality of lips operative to engage the 75 exterior surface of said tooth.

3. The combination of an artificial tooth formed of porcelain or the like and comprising a pair of shoulders on its lateral sides extending upwardly from adjacent the 80 cervical border, a transverse groove connecting the lower ends of said shoulders, a pair of shoulders extending rearwardly from the upper ends of said first-mentioned shoulders, and a transverse groove connecting the 85 ends thereof, whereby a substantially rectangular, outwardly projecting abutment is defined, and a metallic backing inclosing said abutment and engaging said shoulders and said grooves.

4. The combination of an artificial tooth formed of porcelain or the like and comprising a pair of inwardly directed shoulders on its lateral sides extending upwardly from adjacent the cervical border, a transverse 95 groove connecting the lower ends of said shoulders, inwardly directed shoulders on either side of the tooth extending rearwardly from the upper extremities of said first-mentioned shoulders, and a transverse 100 groove connecting said last-mentioned shoulders, whereby a substantially rectangular, outwardly projecting abutment is defined, and a metallic backing inclosing said abutment and engaging said grooves, said backing and a plurality of lips extending from said backing and operative to engage the lateral sides and the lingual portion of said body adjacent said shoulders.

5. The combination with an artificial tooth 110 formed of porcelain or the like and having a plurality of inwardly directed grooves and shoulders terminating at the ends of said grooves and defining a rearwardly and downwardly projecting substantially rectangular abutment and a socket extending therein with its outer opening substantially central of the surface of said abutment, of a sheet metal backing operative to engage within said grooves and having an inwardly 115 directed flange engaging in said socket and a pair of flanged lips operative to engage the lateral surface of said tooth and a lip operative to engage the lingual surface 120 thereof, and a pin having a flanged head 125 extending through said backing centrally of

said flange and within said socket whereby said backing is maintained in operative relation to said tooth.

6. The combination with an artificial tooth having a plurality of laterally disposed, converging shoulders whereby a substantially V-shaped depressed surface is defined on either side of the tooth and a pair of transverse, inwardly directed grooves connecting 10 the ends of said shoulders, of a metal back-

ing operative to engage in said grooves and beneath said shoulders, and means to maintain said backing in operative relation with said tooth.

In witness whereof, I have hereunto set 15 my hand this 23d day of April, A. D., 1915.

LEO E. EVSLIN.
